Primary Examiner — Barbara Fox*Assistant Examiner* — Jamaal Rasheed(74) *Attorney, Agent, or Firm* — MATTHIAS SCHOLL P.C.; Matthias Scholl(57) **CLAIM**

The ornamental design for a dehumidifier, as shown and described.

DESCRIPTION

FIG. 1 is a front view of a dehumidifier showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof;

FIG. 8 is another perspective view thereof; and,

FIG. 9 is an enlarged view of the encircled portion in FIG. 1.

The evenly spaced broken lines in the drawings are for the purpose of illustrating portions of the dehumidifier that form no part of the claimed design. The dash-dot broken lines showing the enlargements in FIGS. 1 and 9 form no part of the claimed design.
